US00D729373S

(12) **United States Design Patent**
Dos Reis et al.

(10) **Patent No.:** **US D729,373 S**
(45) **Date of Patent:** **** May 12, 2015**

(54) **FAN**

(71) Applicant: **Dyson Technology Limited**, Wiltshire (GB)

(72) Inventors: **David Dos Reis**, Malmesbury (GB); **Daniel George Cowen**, Malmesbury (GB); **Peter David Gammack**, Malmesbury (GB); **James Dyson**, Malmesbury (GB); **Tom Vallance Hamilton Crawford**, Malmesbury (GB)

(73) Assignee: **Dyson Technology Limited**, Malmesbury, Wiltshire (GB)

(**) Term: **14 Years**

(21) Appl. No.: **29/466,190**

(22) Filed: **Sep. 5, 2013**

(30) **Foreign Application Priority Data**

Mar. 7, 2013 (EM) 001363766-0005

(51) LOC (10) Cl. **23-04**

(52) U.S. Cl.

USPC **D23/370**; D23/411

(58) **Field of Classification Search**

USPC ..... D23/336, 342, 370-379, 411, 499; D6/309; 415/90, 110, 119, 126, 148, 415/182.1, 183, 207, 208.1, 208.2, 211.2, 415/230; 416/100, 244 R, 246, 247 R; 261/28, 31, 116; 417/84, 177, 198, 417/313, 423.1, 234; 137/338; 392/361, 392/365, 367

See application file for complete search history.

(57) **CLAIM**

We claim the ornamental design for a fan, as shown and described.

DESCRIPTION

FIG. 1 is a perspective view of a fan showing our new design; FIG. 2 is a front view thereof; FIG. 3 is a rear view thereof; FIG. 4 is a side view thereof; FIG. 5 is a side view of the opposite side of FIG. 4; FIG. 6 is a top view thereof; and, FIG. 7 is a bottom view thereof.

The broken lines in the drawings depict the base of the fan and form no part of the claimed design.

1 Claim, 7 Drawing Sheets
